UNITED STATES PATENT OFFICE.

BENJAMIN F. HENDRICKS, OF LAKE CHARLES, LOUISIANA, ASSIGNOR OF ONE-SIXTH
TO JAMES C. McMAHON, OF LAKE CHARLES, LOUISIANA.

APPARATUS FOR MARKING LUMBER AND SIMILAR PRODUCTS.

1,238,293.

Specification of Letters Patent. Patented Aug. 28, 1917.

Application filed August 28, 1916. Serial No. 117,285.

To all whom it may concern:

Be it known that I, BENJAMIN F. HENDRICKS, a citizen of the United States, residing at Lake Charles, in the parish of Calcasieu and State of Louisiana, have invented certain new and useful Improvements in Apparatus for Marking Lumber and Similar Products; and I do hereby declare the following to be a full, clear, and exact description of the invention, such as will enable others skilled in the art to which it appertains to make and use the same.

This invention relates to an apparatus for imprinting or impressing letters, figures, or other characters or designs upon lumber or other material, and has for its object to provide a mechanism which will be simple in construction, comparatively inexpensive to manufacture and more efficient in action than those that have been heretofore proposed.

With these and other objects in view, the invention consists in the novel details of construction and combinations of parts more fully hereinafter disclosed and particularly pointed out in the claims.

Referring to the accompanying drawings forming a part of this specification in which like numerals designate like parts in all the views:—

Figure 1 is a diagrammatic elevational view of an apparatus made in accordance with this invention;

Fig. 2 is a plan view of the parts shown in Fig. 1;

Fig. 3 is a detail view, partly in section, of the inking mechanism illustrated in Fig. 1; and

Fig. 4 is a view similar to Fig. 3 illustrating the brush or other cleaning mechanism with which the apparatus is provided.

1 indicates any suitable shaft journaled in bearings diagrammatically indicated by the dotted lines as at 2, and on said shaft is mounted the wheel 3 provided with the plate 4, controlled by the spring 5, and held in place by any suitable means, as for example, the bolts or screws 6. The plate or plates 4 may be provided with any desired letters, figures, numerals, trade marks, designs, indicated by the numeral 10, or any combination thereof, which it is desired to impress in or print upon lumber or other material. The bearing 2 for the shaft 1 may be conveniently attached to or located

upon any suitable wood working machine or apparatus which is manipulating the lumber or other material to be marked. The said shaft of course, may be disposed either horizontally, or vertically, or in any other desired position.

The wheel 3 is conveniently retained upon the shaft 1 as by the collar or washer 8 which may be secured to the shaft 1 as by means of the bolt or other fastening means 9.

Mounted on the shaft 2 and rigid therewith is an arm 11, provided with a bifurcated end affording the projections or spindles 12 and 13. Upon the spindle 12 is located the frame 14, secured to said spindle 12 as by the set screw 15, and journaled in said frame is the inking roller 16. Rising from said frame 14 is the bracket or support 17 to which is attached the ink container or receptacle 18 provided with the spout or delivery 19, which may be of any suitable shape or construction, but which is preferably of the shape shown, and is further provided with a narrow orifice equal in length to the width of the roller 16, and said orifice is also provided with one or more strips 20, of felt, rubber or other material suitable for spreading the ink smoothly and evenly on the said roller 16. The container 18 is conveniently filled through an orifice at its top which is normally closed by the plug 21. The set screw 15 enables the roller 16 to be adjusted along the spindle 12 and into such a position that the type plates 4 will contact with the said roller at each revolution of the wheel 3, all in a manner that will be readily understood.

Upon the spindle 13 is secured the frame 25 carrying a brush or other wiping means 26. A set screw 27 permits of adjustment of the said brush 26 to and from the periphery of the wheel 3 so that as the said wheel rotates the said brush contacts with the type plates 4, and effectually cleans the same, just before they are subjected to the action of the inking roller 16. A set screw 30 conveniently secures the arm 11 to the shaft 2 and further permits the adjustment of said arm circumferentially of the said wheel 3 to any position desired.

The operation of this improved printing mechanism will be readily understood from the foregoing, but may be summarized as follows:—Suppose for example, that lumber such as 40, is to be marked immediately

- after it is sawed, planed or immediately after any other operation is had thereon:— The shaft 1 is located in such a position that the periphery of the loosely mounted wheel 3 will contact with the traveling surface of said lumber 40 and thus motion will be imparted to said wheel. The plates 4 will successively pass under the brush 26 supported by the rigidly mounted arm 11 and thereby 5 be rendered clean just before they successively contact with the inking roller 16, and receive ink from said roller. The continued rotation of said wheel and plates 4 will cause the latter to successively contact with 10 the traveling surface of the said lumber or other material being marked, whereupon in the instance described, the designs or characters 15 carried by the plates 4 will be successively imprinted upon the said lumber. 20 In order to facilitate the printing operation the said plates 4 are conveniently located in recesses 35 in the periphery of the wheel 3 so that they may normally extend beyond the periphery of said wheel 3 and be forced 25 radially and inwardly against the compression of the spring 5 as they contact with the traveling lumber.

The above operation supposes the wheel to be rotated in the direction of the arrows 30 or in a counter-clockwise direction as illustrated in Fig. 1. Should it be desired, however, to rotate the wheel in an opposite direction, it is only necessary to shift the inking apparatus from the spindle 12 to 35 the spindle 13, and to shift the brush 26 from the spindle 13 to the spindle 12, whereupon the parts will function as above disclosed. Of course, a plurality of wheels such as 3 and inking and printing devices 40 may be operated upon the same shaft 2, if desired, and it is further evident that the wheel 3 may be of any desired size. The inking apparatus or roller may be protected by any suitable cover as is indicated at 41 in 45 dotted lines in Fig. 1. This cover, however, is omitted in Figs. 2 and 3 for the sake of clearness.

It is obvious that those skilled in the art may vary the details of construction, as well 50 as the arrangement of parts without departing from the spirit of the invention, and therefore, I do not wish to be limited to the above disclosure except as may be required by the claims.

55 What I claim is:—

1. In an apparatus of the class described the combination of a shaft; a wheel loosely mounted on said shaft adapted to be rotated by the movement of the material to be

marked; a marking device carried by said 60 wheel; an arm rigidly mounted on said shaft; a pair of spindles carried by said arm; a brush carried by one of said spindles adapted to clean said marking device at each rotation of said wheel; an inking 65 device carried by the other of said spindles adapted to ink said marking device at each rotation of said wheel; and means for radially adjusting the positions of said brush and inking device relative to said marking 70 device, substantially as described.

2. In an apparatus of the class described, the combination of a shaft; a wheel adapted to be rotated by the material to be marked provided with a recess in its periphery and 75 loosely mounted on said shaft; a marking device located in and radially movable in said recess; a spring for controlling the movements of said marking device in said recess; an arm adjustably mounted on said 80 shaft and provided with a pair of spindles; a radially adjustable inking device carried by one of said spindles adapted to supply ink to said marking device; a radially adjustable brush carried by the other of said 85 spindles adapted to clean said marking device; means for readily interchanging the positions of said brush and inking device when the direction of rotation of said wheel is changed; and means to supply ink to 90 said inking device also carried by one of said spindles, substantially as described.

3. In an apparatus of the class described the combination of a shaft; a wheel adapted to be rotated by the material to be marked 95 provided with a recess in its periphery and mounted on said shaft; a marking device located in and radially movable in said recess; a spring for controlling the movements of said marking device in said recess; an arm adjustably mounted on said shaft; a spindle carried by said arm; an inking device comprising a roller and means to supply ink to said roller carried by said spindle and adapted to supply ink to said marking device; means to adjust said inking device to and from said marking device; a second spindle carried by said arm; and a brush located in advance of said inking device adjustably mounted on said second 100 spindle, substantially as described.

In testimony whereof I affix my signature, in presence of two witnesses.

BENJAMIN F. HENDRICKS.
